UNITED STATES PATENT OFFICE.

HARRY E. ROGERS, OF ST. LOUIS, MISSOURI, AND HARRY B. HARLOW, OF ALTON, ILLINOIS, ASSIGNEES TO COMMONWEALTH STEEL COMPANY, OF ST. LOUIS, MISSOURI, A CORPORATION OF NEW JERSEY.

SAND-RAMMING MACHINE.

1,263,602.

Specification of Letters Patent. Patented Apr. 23, 1918.

Application filed November 22, 1917. Serial No. 203,372.

To all whom it may concern:

Be it known that we, HARRY E. ROGERS and HARRY B. HARLOW, citizens of the United States, residing, respectively, at St. Louis, in the State of Missouri, and at Alton, in the county of Madison and State of Illinois, have invented a new and useful Improvement in Sand-Ramming Machines, of which the following is a specification.

10 Our invention relates to a machine specially adapted for ramming or impelling sand into a mold for castings, whereby ramming the sand by hand is obviated and its compactness and homogeneity insured and 15 time and labor saved; also applicable for cleaning castings and metal plates, etching glass, or for coating surfaces with cement mixtures, spraying paint, or for any other purpose accomplishable by its principle of 20 operation.

It consists in features of novelty as hereinafter described and claimed, reference being had to the accompanying drawing forming part of this specification, whereon;

25 Figure 1, is a side elevation of our improved sand ramming machine; Fig. 2, a detailed view to enlarged scale of the rollers and their appendages forming parts of our invention as seen in Fig. 1 (omitting the 30 front portion of their inclosing screen), and Fig. 3, a horizontal section through the machine on line 3--3, in Fig. 2 showing the rollers and their appendages in top plan view.

35 Like letters and numerals of reference denote like parts in all the figures.

Our invention consists essentially of two opposite parallel revoluble rollers a , a' , which are preferably, partly in contact circumferentially with each other and otherwise specially constructed as follows:

40 From each end of the roller a which, in the present case, is preferably, arranged between the two opposite sides 1 of a frame b (see particularly Figs. 2 and 3) projects an axle 2 which is mounted in a suitable bearing 3 formed in the corresponding side 1 of the frame b , and on the axle 2 beyond one side 1 of the frame b is fixed a pulley 4 (omitted in Fig. 2). To the top of each side

1 is fixed the lower end of a channel or other suitable upright bar c which is of suitable height or length and secured at its upper end to the underside of a platform d on which is mounted a suitable motor e having 55 a central shaft or axle 5, and on the shaft 5 is fixed a drive pulley 6 which connects with the pulley 4 on the axle 2 of the roller a by an endless belt 7, the whole being preferably, suspended from an overhead framework or scaffold f , either by a rod 8 secured to the platform d and passing freely through an eyebolt 9 fixed to a member of the scaffold f as shown, or in any other suitable manner, whereby the platform d with 60 its appendages is free to swing in all directions and the roller a with its frame b correspondingly moved in an approximately horizontal plane.

Each roller a , a' , (see Figs. 2 and 3) is 70 preferably, formed circumferentially for a suitable distance from each end with a plain or smooth surface 11, the corresponding surfaces 11 of the rollers a , a' , being in frictional contact with each other, while the intervening or middle circumferential surface of each roller a , a' , is formed with a series of longitudinal corrugations 12, either wedge-shaped as shown, or of any other desired configuration, the plain surfaces 11 of the rollers a , a' , being preferably, diametrically somewhat greater than the corrugated surfaces 12 so as to form a space between the corrugated portions of the rollers a , a' . 75

The idle roller a' is preferably, axially 80 mounted at each end in a bearing 3' formed in the lower end of a link g which is dependent from and pivoted at its upper end to the corresponding arm or side member 13 of a frame b' which straddles the sides 1 of the frame b , the arms 13 being hinged at their free ends to the axle 2 of the roller a and connected together at their other ends by a transverse member 14, from which projects outwardly a handle 15 whereby the frame b' with the links g and roller a' can be raised or lowered about the axle 2 of the roller a when desired into horizontal central alignment with the roller a , according to the 90 position of the latter when moved in any di- 100

rection from the vertical line of its suspension from the scaffold f in the operation of the machine.

For maintaining the idle roller a' normally in circumferential contact with the roller a we preferably, use a spring 16 having at one end a housing 17 formed in each link g and at its other end opposite to the housing 17, a housing 18 formed on the inside face of the transverse member 14. Within the housing 18, between its inner end and the corresponding end of the spring 16 is a follower 19 which is engaged by the end of a screw-bolt 20 operated from the outside 15 of the frame b' whereby the compression of the spring 16 and consequent pressure of the roller a' against the roller a is regulated, a further function of the spring 16 being to permit the yielding of the roller a' when subjected to undue pressure and allowing large pieces of material to pass between the rollers a, a' , without damaging the machine.

From the scaffold f is suspended a chute h the upper end of which is preferably, inclosed 25 by a ring 21 which is pivoted at two opposite points 22 (Fig. 1) of its circumference to the inside of an outer ring 23 having two opposite trunions 24 which are at right angles to the pivotal points 22 of the inner ring 30 21 and journaled in brackets 25 fixed to the scaffold f , whereby the chute h can be moved in any direction, in an approximately horizontal plane. The chute h which opens at its lower end between the upper halves of 35 the rollers a, a' , and directly over the space between the converging corrugations 12 of the respective rollers a, a' , is secured thereto at the upright bars c carrying the roller a and its frame b , by a band 26, or otherwise, as found most suitable. Furthermore, 40 the chute h is preferably, made in two (or more) sections 27, 28, adapted to telescope with each other as shown for enabling the chute h to automatically adjust itself to the 45 varying positions of the rollers a, a' , about their point of suspension 9. Fixed to the frame b' and adapted to be moved therewith when raised or lowered about the axle 2, is a shield or screen 29 which incloses the lower

parts of the rollers a, a' , whereby the latter 50 and the operator are protected from injury.

In operation, rotation being imparted to the rollers a, a' , by the belt 7 driven by the motor e , and to the roller a' by the frictional contact therewith of the roller a in the directions indicated by the respective arrows in Fig. 1, sand x supplied to a hopper i fixed to the scaffold f over the mouth of the chute h , falls by gravity into the latter and is directed thereby into the space between the 60 converging corrugations 12 of the respective rollers a, a' , and being seized and compacted by the corrugations 12 is impelled by the latter through the said space at an accelerated velocity and in a line tangent to the 65 point of contact of the rollers, a, a' , and due to the momentum so caused, is solidly packed or rammed in a mold for casting. Or the same principle may be used for impelling other material in a disintegrated or 70 liquid form in lieu of sand, into a receptacle or against a surface according to the purpose for which the machine may be applied.

We claim:

1. In a machine of the character described, 75 two opposite longitudinally corrugated revoluble rollers adapted to seize and impel a continuous stream of material, the said rollers being axially mounted in suitable bearings and movable therewith about a common point of suspension, and means for changing the relative positions of the rollers circumferentially about each other in the plane of their revolution.

2. In a machine of the character described, 85 two opposite longitudinally corrugated revoluble rollers adapted to seize and impel a continuous stream of material, the said rollers being mounted in suitable bearings and movable therewith about a common 90 point of suspension, a member adapted to carry the axle of one of the rollers, and means for raising and lowering the said member hingewise about the axle of the other roller.

HARRY E. ROGERS.
HARRY B. HARLOW.
